UNITED STATES PATENT OFFICE.

FRANK FORSYTH, OF HAVANA, ILLINOIS.

DESIGN FOR A DIE FOR STAMPING SHOVELS.

SPECIFICATION forming part of Design No. 32,365, dated March 20, 1900.

Application filed February 15, 1900. Serial No. 5,392. Term of patent 7 years.

To all whom it may concern:

Be it known that I, FRANK FORSYTH, a citizen of the United States, residing at Havana, in the county of Mason and State of Illinois, have invented and produced a new and original Design for a Stamping-Die, of which the following is a specification.

In the drawings forming part of this specification, Figure 1 is a plan, Fig. 2 is a side elevation, and Fig. 3 is an end elevation, of a die illustrating my new design.

The essential feature of my design is a plate, as 1, from which rises a die approximately **H**-formed. The side members 2 of the die are separate and parallel and they have diverging end extensions describing straight lines. The end extensions on each member 2 extend in a direction away from the opposite member 2, and the member 3 con-

nects members 2 and gives the die the general form of a letter **H**. One line of member 3 is midway between the ends of members 2, and the contour of such line in end elevation is arc-formed, with the center higher than the ends. The members 2 are highest at their ends. They are depressed gradually toward their centers, and the end extensions are depressed gradually away from their conjunction with the parallel portions.

What I claim is—

The design for a stamping-die herein shown and described.

In testimony whereof I sign my name in the presence of two subscribing witnesses.

FRANK FORSYTH.

Witnesses:

GEO. H. RENAULT,
F. H. O'BEIRNE.
